Filed Sept. 21, 1966, Ser. No. 3,947

Term of patent 14 years

(Cl. D58—8)

FIG.1.

FIG.2.

FIG.3.

FIG.4.

FIG.5.

FIG.6.

FIG. 1 is a front elevational view of a bottle showing our new design;

FIG. 2 is a side elevational view thereof;

FIG. 3 is a top view thereof;

FIG. 4 is a bottom view thereof;

FIG. 5 is a sectional view thereof taken along the line 5—5 in the direction shown; and

FIG. 6 is a sectional view thereof taken along the line 6—6 in the direction shown.

The characteristic feature of the new design resides in a bottle having a pinched central portion constituting a symmetrical restriction about the vertical axis of the bottle, which restriction is a flattened ovoid in section, the flattened sides being substantially parallel to the long axis of the ellipse.

We claim:

The ornamental design for a bottle, as shown and described.
